[57] CLAIM

The ornamental design for a case for an audio tape cassette, as shown and described.

DESCRIPTION

FIG. 1 is a perspective view of a case for an audio tape cassette, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a cross-sectional view taken on line 8—8 of FIG. 2;

FIG. 9 is a cross-sectional view taken on line 9—9 of FIG. 2; and,

FIG. 10 is a perspective view thereof from the side opposite that shown in FIG. 1, showing the case open. The partial showing of the trapezoidal element in FIG. 10 is understood to have the same appearance as that trapezoidal element shown in the lower portion of the same figure.
